FREDRIK TESTOR, OF STOCKHOLM, SWEDEN.

CONTACT DEVICE FOR APPARATUS FOR LIGHTING OR EXTINGUISHING GAS.

SPECIFICATION forming part of Letters Patent No. 776,154, dated November 29, 1904.

Application filed August 16, 1904. Serial No. 220,938. (No model.)

To all whom it may concern:

Be it known that I, FREDRIK TESTOR, manufacturer, a subject of the King of Sweden and Norway, and a resident of Surbrunnsgatan 5 49, Stockholm, in the Kingdom of Sweden, have invented certain new and useful Improvements in Contact Devices for Apparatus for Electric Lighting or Extinguishing of Gas, of which the following is a specification.

- 10 The present invention relates to a contact device adapted for electric ignition of gas-jets when a bolt is pushed and for their extinction when the bolt is withdrawn. The contact device is constructed so as to give 15 full security of obtaining in the latter case a contact of sufficient duration to effect the closing of the gas-cock or the gas-inlet and the extinguishing of the gas, so that the latter will not continue burning on the bolt being 20 withdrawn when a person leaves the apartment—for instance, a water-closet. In the electric ignition of gas-jets an electromagnet is well known to be used, which is put in action by closing an electric current, causing a gas- 25 cock to be turned or a gas-inlet to be opened, so that gas escapes from the burner, said gas being ignited by means of a platinum wire, for instance, which is made to glow when the aforesaid current is closed or by some other 30 means. For putting out gas-flames the electromagnet subsequently must be actuated anew, so as to enable it to turn the gas-cock back to its closed position or to shut the gas-inlet. Experience has proved, however, that 35 the current required for returning the gas-cock into its closed position must not be of too short a duration, since in that case it may easily happen that no closing of said cock takes place, which is evidently an important 40 circumstance if the gas-jet is supposed to be closed when a person leaves the apartment where it is situated. This inconvenience is obviated in the present invention by causing the contact to be of longer duration in clos- 45 ing the current serving for extinction—returning the gas-cock—than in closing the other current—for opening the passage of the gas to the burner.

In the accompanying drawings the contact 50 device referred to is illustrated in combina-

tion with a door-bolt in two different positions in Figures 1 and 2.

a is the bolt, which is shifted by means of the button *b*. The contact device proper is composed of a double lever *c*, normally held 55 lifted by a spring, so as to be in the path of the bolt, which is cut off obliquely at its front edge, said lever carrying a contact-arm *d*, electrically connected thereto and being forked in the drawings. This contact-arm is adapt- 60 ed to oscillate over two contacts *e* and *f*, connected one, *e*, with one branch of a circuit actuating the gas-cock or the device for admitting gas to the burners for closing it and the other, *f*, with one branch of a circuit 65 serving to open the gas-cock or the device for admitting gas to the burners. The other branch, *g*, which may be common to both circuits, is connected, for instance, with the plate on which the lever *c* with the contact- 70 arm *d* is so arranged as to be inclosed in the circuit. The end of the lever *c* which points away from the bolt is connected with a plunger fitting closely in a cylinder *h*, which should be arranged to rock so as to adjust itself to 75 the different positions of the plunger in the oscillating movements of the lever *c*.

When the bolt *a* is pushed in closed position—for instance, from within—the corre- 80 sponding end of the lever will be depressed and a pin *i*, attached to this end, finally snaps under the bolt, as shown in Fig. 2, so that the lever *c* will be retained in its position as long as the bolt remains closed. By this movement of the lever the contact-arm *d* is 85 turned first over the contact *e* for closing the gas-cock or the gas-inlet, and subsequently over the contact *f*, causing the gas-cock or the gas-inlet to be opened and the gas to be lighted. The plunger is simultaneously pulled up into 90 the cylinder *h*. When the bolt *a* is withdrawn, the lever *c* will be returned to its former po- 95 sition and the contact-arm *d* at the same time passing over the contact *e* will cause the gas-cock to be returned to its closed position, and consequently effect the extinction of the gas. This movement of the arm *d* over the contact *e*, however, is much slower than over the contact *f*, since the plunger at this portion of the turning movement of the arm experiences an 100

increasing resistance from the air beneath it in the cylinder, said air thus impeding the movement of the lever *c* in this part of its turning and compelling the contact-arm *d* to 5 pass over the contact *e* so slowly as to assure that the current closed through *e* will have had time to effect the closing of the gas-cock or of the gas-inlet.

Having now particularly described and ascertained the nature of my said invention and in what manner the same is to be performed, I declare that what I claim is—

An improved contact device for electric lighting and extinguishing of gas when a bolt 15 is being pushed or withdrawn, consisting of

a rocking lever *c* one end of which is situated in the path of the bolt and the other end of which is connected with a plunger fitting closely in a cylinder *h*, said lever being connected with a contact-arm *d* which at the 20 movement of the lever caused by the bolt moves over contacts *e*, *f* of the circuits in which the devices for closing and opening the gas-inlet are located.

In witness whereof I have hereunto set my 25 hand in presence of two witnesses.

FREDRIK TESTOR.
